INVENTOR.
EDWARD S. SMITH.

BY *Lockwood Lockwood*
ATTORNEYS.

UNITED STATES PATENT OFFICE.

EDWARD S. SMITH, OF ANDERSON, INDIANA, ASSIGNOR TO WILLIAM H. FORSE, JR.,
OF ANDERSON, INDIANA.

WINDOW-SHADE BRACKET.

Application filed August 12, 1921. Serial No. 491,721.

To all whom it may concern:

Be it known that I, EDWARD S. SMITH, a citizen of the United States, and a resident of Anderson, county of Madison, and State 5 of Indiana, have invented a certain new and useful Window-Shade Bracket; and I do hereby declare that the following is a full, clear, and exact description thereof, reference being had to the accompanying drawings, in which like numerals refer to like 10 parts.

This invention relates to a window shade bracket wherein the window shade may be moved back and forth, against and away 15 from the window in order to clear the ventilator sections of some windows and is of the same general type illustrated in Patent No. 704,894.

The main feature of the invention lies in 20 the mechanism for moving the entire window shade, to and from the window, whereby it may either lie adjacent the window when so desired, or be spaced therefrom when necessary because of the extended position taken by certain types of windows and 25 ventilators. This is accomplished by mounting the shade roller upon a traveling crane construction in turn supported at each end on horizontally and outwardly extending 30 tracks for permitting the positioning and spacing thereof from the window casing.

The full nature of this invention will be 35 understood from the accompanying drawings and the following description and claims.

Fig. 1 is a front elevation of a window casing with a movable window shade mounted thereon, parts being broken away. Fig. 2 is a side elevation of the supporting 40 bracket with the movable window shade mounted thereon, taken on a line 2—2 of Fig. 1. Fig. 3 is a side elevation of a portion of the supporting bracket having the outer end thereof broken away, taken on the 45 line 3—3 of Fig. 1. Fig. 4 is a perspective view showing the development of the guide cords. Fig. 5 is an enlarged side elevation, with parts broken away, of the supporting bracket and traveling block. Fig. 6 is an 50 enlarged plan view looking down on the supporting bracket and traveling block. Fig. 7 is an enlarged front elevation of a portion of the supporting bracket and traveling block.

55 In the drawings there is shown a win-

dow casing 10 upon which is mounted a window shade 11 of the usual type, which is suspended from the shade roll 11'. The shade 11 and the shade roll 11' are of the usual type commonly used, and instead of 60 being supported in the usual fixed brackets to the window casing, the roll is supported in a traveling block comprised of side plates 12 having a recess for securing the supporting ends 13 of the roll 11'. The side plates 65 12 are supported upon the flanged wheels 14 which are mounted upon the track 15 so as to freely roll thereon. The track 15 is rigidly secured to a bracket 16 which is firmly fixed upon each side of the window to the 70 casing 10. Said bracket extends laterally and forwardly from the window and is supported at its outer end by the brace 17 which is secured at its outer end to the track and at the other end to the bracket 16. By 75 means of this arrangement the carrying block and the window shade may be moved forwardly on the track away from the window or rearwardly thereon to adjacent the window.

For maintaining the traveling blocks mounted on each side of the window parallel with each other in their movements, there is provided an endless cord 18 which passes about the forward pulleys 19 mounted on 85 the spindles 20 at the forward ends of the supporting track, and about the rear side pulleys 21 pivotally supported on the brackets 16 by the ears 22. The right hand traveling block is secured to the upper 90 strand of the cord 18 by means of the engaging plates 23 and the set screw 24, so that the right hand block travels in the direction taken by the upper right hand strand. The left hand traveling block is secured in 95 the same manner to the lower strand of the cord 18, as shown in Fig. 3. As the upper right hand strand and the lower left hand strand of said cord move in the same direction with the same rate of movement, said 100 cord will maintain both driving blocks in the same relative position to the window and in a parallel plane thereto, whereby the shade and roller will be maintained at all times parallel to the window regardless of 105 the movement thereof. The cord engaging plates 23 are maintained at the outer end of the arm 25 which is secured to one of the side plates 12 of each of the carrying blocks, as shown in Fig. 6, and is adapted to clamp 110

the tube 26 in which the plates 23 and screw 24 are mounted and through which the cord 18 passes. By means of the arm 25 the cord 18 is spaced from the traveling blocks and is rigidly connected to each of said blocks for imparting the same relative movement thereto. The traveling blocks and shade may be moved back and forth to and from the window by any suitable means, such as 10 a cord and pulley, or by a window stick as may be desired.

The invention claimed is:

1. The combination with a window casing and a shade therefor, of means for supporting said shade adjacent said window casing, comprising laterally extending tracks, traveling blocks mounted thereon for supporting said window shade, and a single band which said traveling blocks are secured for maintaining them at an equal distance from said window casing and said shade parallel therewith in moving said shade on said track to and from said window.

2. In a window shade support of the character described, the combination with a

track, an endless cord supported thereby, and a shade supporting block slidably supported on said track, of means for securing said cord to the block and supported by said block, comprising a clamping portion securing said cord, and an aligning portion engaging and maintaining said cord in parallel relation to said track and retaining said block upon said track.

3. In a window shade support of the character described, the combination with a supporting track, and an actuating cord in spaced relation therewith, of a shade-supporting block, comprising a plurality of rollers engageable upon said support, a spaced framework for straddling said track and securing said rollers, and an outrigger construction extending axially of said rollers and outwardly from said framework for engagement with said cord and maintaining said framework upon said track.

In witness whereof, I have hereunto affixed my signature.

EDWARD S. SMITH.
